[57] CLAIM

The ornamental design for mirrored retail display platform, as shown and described.

DESCRIPTION

FIG. 1 is a front elevational view of a mirrored retail display platform showing our new design;

FIG. 2 is a rear elevational view thereof;

FIG. 3 is a top plan view thereof;

FIG. 4 is a bottom plan view thereof;

FIG. 5 is a right side elevational view thereof, the left side being a mirror image thereof; and,

FIG. 6 is a sectional view thereof showing the slant and configuration of the mirrors.

FIG. 1

FIG. 2

FIG. 3

FIG. 4

FIG. 5

FIG. 6
